CLAIM

The ornamental design for floating eyeglasses, as shown and described.

DESCRIPTION

FIG. 1 is a left, front perspective view of floating eyeglasses taken from above showing my new design;
FIG. 2 is a right, rear perspective view thereof taken from below and from the opposite side;
FIG. 3 is a front view thereof;
FIG. 4 is a top view thereof; and,
FIG. 5 is a right side view thereof, the left side being a mirror image of that shown in FIG. 5.

FIG. 1

FIG. 2

FIG. 3

FIG. 4

FIG. 5
